US00D608894S

(12) **United States Design Patent**
Arbesman et al.

(10) **Patent No.:** US D608,894 S
(45) **Date of Patent:** ** Jan. 26, 2010

(54) **ADHESIVE PLANTAR FASCIA BRACE**

(76) Inventors: **Ray Arbesman**, 42 Burton Road, Toronto, ON (CA) M5P 1V2; **Kevin Jardine**, 505 Eglinton Avenue West, Suite 302, Toronto, ON (CA) M5N 1B1

(**) Term: **14 Years**

(21) Appl. No.: **29/332,065**

(57) **CLAIM**

An ornamental design for an adhesive plantar fascia brace, as shown and described.

DESCRIPTION

FIG. 1 is a top view of the adhesive plantar fascia brace showing our new design; and,

FIG. 2 is a perspective view of the adhesive plantar fascia brace when in condition for use.

The broken lines shown in the drawings are for illustrative purposes only and form no part of the claimed invention.
